WORK-SUPPORTING MEANS FOR BOX-MAKING MACHINES

Glen P. Woodbury, Mountain Lakes, N. J., assignor to Stapling Machines Co., a corporation of Delaware

Application November 25, 1942, Serial No. 466,957

8 Claims. (Cl. 1—8.2)

This invention relates to box or crate making machines and particularly to machines for stapling binding wire to box or crate parts.

It is an object of the invention to provide certain improvements in the type of machine shown and described in United States Patent No. 2,304,510, dated December 8, 1942, and particularly to provide certain improvements in the mechanism for supporting the box parts during a staple-driving operation.

In the drawings,

Fig. 1 is a side elevation of a work-supporting unit embodying the invention, and a portion of a stapling unit, showing the parts in their initial or non-operative positions.

Fig. 2 is a top plan view of the same, partially sectioned, on line 2—2 of Fig. 1.

Fig. 3 is a perspective view of the wedge member of the unit.

Fig. 4 is a perspective view of one of the movable plate members of the unit.

Fig. 5 is a perspective view of one of the stationary plate members of the unit.

Fig. 6 is a perspective view of one of the plate spacer members of the unit.

Fig. 7 is similar to Fig. 1 but shows the parts in their operative positions.

Fig. 8 is an enlarged side elevation of the wedge member and cooperating plate members in the operative positions shown in Fig. 7.

In the machine of said Patent No. 2,304,510, box parts are fed beneath stapling units which form staples from staple-stock wire fed thereto, and drive the staples into the box parts. Prior to each staple-driving operation, the work is positioned relative to the staple driver and supported in such position during the staple-driving operation. In said patent, this positioning and supporting operation is performed by a movable work-supporting member automatically adjustable in accordance with variations in the surface level of the work, to present uniformly the surface of the work to the action of the staple driver. The work-supporting unit of said patent comprises a body member, a movable work-supporting member pivotally connected in parallelism to the body member by parallel linkage, and a wedge member movable between the body member and the work-supporting member to raise the latter and hold it in raised position during the staple-driving operation. Such a work-supporting unit and its operation are fully shown and described in said Patent No. 2,304,510, reference to which is hereby made for a detailed description.

In the operation of the work-supporting unit

of said patent, it has been found that the wedge member sometimes slips back under the force of the staple driver, permitting the work-supporting member to drop and causing a defective staple-driving operation. This slippage of the wedge member is due to the insufficiency of the frictional holding power of the two frictional surfaces between the wedge member and the other parts of the unit when oil film accumulates on such surfaces.

The present invention is directed to means for increasing the frictional engagement between the wedge member and the other parts of the work-supporting unit, thus increasing the resistance to slippage of the wedge member and improving the efficiency of the work-supporting unit.

As hereinafter described in detail, such means comprises a plurality of thin metal plates (four in the illustrative machine) preferably fork-shaped and constructed and arranged to cooperate with the wedge member and the other parts of the work-supporting unit to increase the frictional engagement between the wedge member and such other parts. As illustrated, two of these plates are separated by spacers and securely fastened to the under surface of the movable work-supporting member of the work-supporting unit. These plates will hereinafter be referred to as the fixed plates. The other two plates are secured to the wedge member and move therewith. They will be referred to hereinafter as the movable plates.

Preferably, the top surface of each of the four plates and of the wedge member, as well as the upwardly-inclined surface of the body member, are provided with crosswise grooves which function to break the oil film and to wipe away dirt.

Referring to Fig. 1, the work-supporting unit comprises a body member 1 and a work-supporting member 2 connected together at either end by links 3 fastened by pins 4, thus forming a parallel linkage. To elevate the work-supporting member 2 to required height, a wedge member 5 (Fig. 3), preferably fork-shaped, is interposed between the body member 1 and the work-supporting member 2 to raise the latter. In Figs. 1, 2, and 4, and particularly in Fig. 4, is shown one of the movable plates 6, preferably fork-shaped, as hereinbefore stated, and having a portion of its solid end bent at a right angle. The bent end of each movable plate 6 is provided with a hole 7 to receive a horizontal stud 8 projecting from the body portion of the wedge member 5. The holes 7 in the movable plates 6 are located respectively so that when the two movable

plates 6 are assembled in position on the studs 8 (Fig. 8) they will be separated a distance equal to the thickness of one of the fixed plates, hereinafter described. The two movable plates 6 are held in position on the wedge member 5 by compression springs 9 which are coiled about the studs 8 and interposed between a stop member 10 carried by movable work-supporting member 2 and the bent portions of the movable plates 6. Thus, plates 6 move with wedge member 5. Preferably, both movable plates 6 are provided with crosswise grooves 11 in the top surface of the forked ends.

One of the fixed plates (identified by the reference numeral 12) is shown in Fig. 5. Each fixed plate 12 is preferably fork-shaped and provided with crosswise grooves 11 in the top surface of the forks. The head of the plate is provided with a hole 13 to receive a fastening member. In the completed assembly, fixed plates 12 are spaced from each other and from work-supporting member 2 by spacers 14 of a thickness equal to the thickness of a movable plate 6, so as to provide a telescopic engagement between the plates 6 and 12. Each spacer 14 is provided with a hole 15 (Fig. 6) so that fixed plates 12 and spacers 14 may be secured to the recessed under-surface of work-supporting member 2 by a screw 16.

It will be seen by reference to Figs. 1 and 2 that the fixed plates 12 secured to work-supporting member 2, and the movable plates 6 secured to wedge member 5, are arranged so that they alternate with each other in their relative positions. This provides several frictional contact surfaces in addition to the contact surfaces provided by wedge member 5.

It will also be noted that the grooved surfaces contact solid surfaces in each instance, thereby providing a series of wiping edges which will prevent any excess accumulation of oil or dirt between each set of plates.

In operation, the action of the wedge member 5 to elevate the work-supporting member 2 until the work is contacted and supported (Figs. 7 and 8) is the same as the action of the wedge member in said Patent No. 2,304,510. When the staple-driving occurs, the wedge member 5 has been moved up the inclined surface of body member 1 by means of the springs 9; and the load of stapling is transmitted through the fixed plates 12, the movable plates 6, and the wedge member 5, to body member 1. Since the fixed plates 12 are secured to the work-supporting member 2, and the movable plates 6 are secured to the wedge member 5, the wedge member 5 cannot slide down the inclined surface of body member 1 without slippage at the contact surfaces of movable plates 6, fixed plates 12, and work-supporting member 2. These contact surfaces, being under vertical pressure of the stapling load, produce friction forces which counteract the slippage tendency. The total value of these friction forces is directly proportional to the number of contact surfaces (in this case, six) and is sufficient to prevent the wedge member 5 from sliding down, thus holding the work-supporting surface of member 2 in contact with the work under extreme loads.

As fully described in said Patent No. 2,304,510, wedge member 5 is normally held in retracted position against the action of springs 9 by a cam 17 which contacts a depending arm 18 carried by wedge member 5 (Fig. 1). Cam 17 is keyed to a shaft 19 which is rotated in timed relation to the operation of a staple driver 20 (Fig. 7)

to permit the springs 9 to move wedge member 5 just prior to a staple driving operation (Fig. 7) to raise work support 2 into supporting contact with box parts 21 and hold the box parts in contact with a lobe 22 carried by stapler body 23 during a staple-driving operation (Fig. 7), all as described in said Patent No. 2,304,510. Upon completion of the staple-driving operation, cam 17, operating on arm 18, retracts wedge member 5, permitting work-supporting member 2 to drop from the position shown in Fig. 7 to the position shown in Fig. 1.

Among other advantages, this invention provides an improved automatically adjustable work support adapted to perform efficiently under adverse conditions and thus to contribute to a uniform stapling operation and a uniform stapled product.

It will be understood that the invention is not to be limited to the illustrative embodiment and that all of the inventive features need not be used conjointly, as they may be used to advantage separately or in various combinations as defined in the subjoined claims.

I claim:

1. In a box-making machine having fastener-driving means, an adjustable work-supporting unit comprising a body member, a work-supporting member, a wedge member movable between the body member and the work-supporting member to raise the latter member and when raised to hold it in raised position during a fastener-driving operation, means to move the wedge member, a plate secured to the wedge member and having frictional engagement with the work-supporting member, and a plate secured to the work-supporting member and having frictional engagement with the wedge member.

2. In a box-making machine having fastener-driving means, an adjustable work-supporting unit comprising a body member, a work-supporting member, a wedge member movable between the body member and the work-supporting member to raise the latter member and when raised to hold it in raised position during a fastener-driving operation, means to move the wedge member, a plate secured to the wedge member and having frictional engagement with the work-supporting member, and a plate secured to the work-supporting member and having frictional engagement with the first-mentioned plate.

3. In a box-making machine having fastener-driving means, an adjustable work-supporting unit comprising a body member, a work-supporting member, a wedge member movable between the body member and the work-supporting member to raise the latter member and when raised to hold it in raised position during a fastener-driving operation, means to move the wedge member, a plate secured to the work-supporting member, and a plurality of plates secured to the wedge member, the plate secured to the work-supporting member having frictional engagement with plates secured to the wedge member.

4. In a box-making machine having fastener-driving means, an adjustable work-supporting unit comprising a body member, a work-supporting member, a wedge member movable between the body member and the work-supporting member to raise the latter member and when raised to hold it in raised position during a fastener-driving operation, means to move the wedge member, a plate secured to the wedge member, and a plurality of plates secured to

the work-supporting member, the plate secured to the wedge member having frictional engagement with plates secured to the work-supporting member.

5. In a box-making machine having fastener-driving means, an adjustable work-supporting unit comprising a body member, a work-supporting member, a wedge member movable between the body member and the work-supporting member to raise the latter member and when raised to hold it in raised position during a fastener-driving operation, means to move the wedge member, a plurality of plates secured to the wedge member, and a plurality of plates secured to the work-supporting member, the plates secured to the wedge member having frictional engagement with plates secured to the work-supporting member.

6. In a box-making machine having fastener-driving means, an adjustable work-supporting unit comprising a body member, a work-supporting member, a wedge member movable between the body member and the work-supporting member to raise the latter member and when raised to hold it in raised position during a fastener-driving operation, means to move the wedge member, a plate secured to the wedge member and having frictional engagement with the work-supporting member, and a plate secured to the work-supporting member and having frictional engagement with the wedge member, one of said plates having a plurality of grooves or recesses on one surface.

7. In a box-making machine having fastener-driving means, an adjustable work-supporting unit comprising a body member, a work-supporting member, a wedge member movable between the body member and the work-supporting member to raise the latter member and when raised to hold it in raised position during a fastener-driving operation, means to move the wedge member, a plate secured to the wedge member and having frictional engagement with the work-supporting member, and a plate secured to the work-supporting member and having frictional engagement with the wedge member, the wedge member having grooves or recesses on the surface having frictional engagement with a plate.

8. In a box-making machine having fastener-driving means, an adjustable work-supporting unit comprising a body member, a work-supporting member, a wedge member movable between the body member and the work-supporting member to raise the latter member and when raised to hold it in raised position during a fastener-driving operation, means to move the wedge member, a plate secured to the wedge member and having frictional engagement with the work-supporting member, and a plate secured to the work-supporting member and having frictional engagement with the wedge member, the body member having grooves or recesses on the surface having contact with the wedge member.

GLEN P. WOODBURY.
